UNITED STATES PATENT OFFICE.

WILLIAM C. FISHER, OF MIDDLETOWN, CONNECTICUT, ASSIGNOR TO THE RUSSELL MANUFACTURING COMPANY, OF MIDDLETOWN, CONNECTICUT.

CARTRIDGE RECEPTACLE OR BELT.

1,209,136.

Specification of Letters Patent. Patented Dec. 19, 1916.

Application filed June 8, 1916. Serial No. 102,432.

To all whom it may concern:

Be it known that I, WILLIAM C. FISHER, a citizen of the United States, and a resident of Middletown, in the county of Middlesex and State of Connecticut, have invented certain new and useful Improvements in Cartridge Receptacles or Belts; and I do hereby declare the following to be a full, clear, and exact description of the invention, 10 such as will enable others skilled in the art to which it appertains to make and use the same.

This invention relates to improvements in cartridge receptacles or belts and more particularly to the pocket construction,—one object of the invention being to so construct a woven fabric cartridge belt that its outwardly projecting pockets shall be provided without the necessity for and the expense 15 incident to the weaving of the pockets integral with the body fabric of the belt as heretofore proposed.

A further object is to so construct a woven fabric cartridge belt that its cost of manufacture shall be reduced to a minimum without sacrifice of strength and efficiency.

With these and other objects in view, the invention consists in certain novel features of construction as hereinafter set forth and 30 pointed out in the claims.

In the accompanying drawings, Figure 1 is a diagrammatical view; Fig. 2 is a perspective view of the woven blank, and Fig. 3 is a perspective view, partly in section 35 showing a set of connected pockets.

1 represents a woven fabric blank which will be of sufficient length to provide a belt of standard size, and have a width about double that of a cartridge belt as now commonly employed. One half 2 of this blank above the longitudinal center line thereof, is woven flat while the portion 3 of the blank 40 at the other side of or below the center line is woven with such fullness that when the blank is folded upon itself on said center line and stitched transversely at intervals, as at 4, pockets 5 will be formed which will project outwardly only from the flat woven or body portion 2 of the belt.

50 In providing the necessary fullness in the portion 3 of the blank, I may employ more material in the warp threads for said portion 3 than for the flat portion 2 of the blank and during the process of weaving of the

blank, a comb may be employed to gather 55 and hold the material of the portion 3, so that a greater length of fabric will be woven in said portion 3 than in the portion 2 of the blank,—such excess of length of the fabric of the portion 3 over the length of fabric 60 woven in the portion 2 of the blank causing the portion 3 to bulge outwardly. In order that the bulged portion 3 may be approximately the same in texture as the portion 2, I may insert at intervals, filler threads 6 65 which extend only from the center line to the free edge of the portion 3 of the blank as indicated in Fig. 1. Instead of employing supplemental filler threads 6 for the purpose above stated, I may use more or larger warp 70 threads in the portion 3 of the blank than in the portion 2.

Before folding the blank as above mentioned to form the pocketed belt, I may secure a reinforcing strip 7 to said blank 75 lengthwise thereof, so that it will extend appreciable distances laterally in both directions from the center line of the blank. The strip 7 may be stitched or otherwise secured to the blank and it may consist of woven 80 fabric or of woven fabric having metal reinforcement. When the blank is now folded upon itself and stitched to form the pockets as previously explained and indicated in Fig. 3 the strip 7 will constitute reinforce- 85 ment for the bottoms of the pockets.

Having fully described my invention what I claim as new and desire to secure by Letters-Patent, is:—

1. A plurality of connected cartridge 90 pockets comprising woven fabric having fullness in one portion thereof and folded upon itself and secured transversely at intervals, forming a plurality of pockets having flat back portions and outwardly bulged 95 front portions.

2. A cartridge receptacle comprising a woven blank having a fullness at one side of the center thereof and folded on said center line, and fastening means securing the 100 front part having the fullness therein to the flat back portion, forming a receptacle.

3. A cartridge receptacle comprising a piece of woven fabric having a portion at one side of its center woven flat and a part 105 at the other side of the center woven with a fullness, said fabric piece having the two parts thereof disposed one in front of the

other and secured transversely, forming a receptacle having a flat back and a bulged front.

4. A cartridge receptacle comprising a woven fabric piece having a fullness in approximately one half thereof and having the other portion woven flat, reinforcing means centrally located and secured to both of said portions of the fabric piece, said fabric piece and reinforcing means being folded and the portion having the fullness dis-

posed in front of the flat portion of the piece, and means securing the two parts of the fabric piece to form a receptacle having a reinforced bottom.

In testimony whereof, I have signed this specification in the presence of two subscribing witnesses.

WILLIAM C. FISHER.
